SAFETY RAZOR

Henry W. Uhl, Dobbs Ferry, N. Y.

Application August 26, 1931, Serial No. 559,549

17 Claims. (Cl. 30—12)

This invention relates to safety razors and more particularly to safety razors which are provided with means by which the razor blade may be sharpened without removing the blade from the holder and it is an object of this invention to provide an improved device of the type described in which means are provided which may be readily operated to sharpen the blade without removing the blade and which means is normally so held as not to interfere with the ordinary use of the razor. It is also an object of this invention to provide in a razor of the type described a means which sharpens both edges of a double edged blade simultaneously.

15 In the drawing—

Fig. 1 is a view in section of a safety razor constructed in accordance with this invention, the parts being shown as positioned for use;

Fig. 2 is a view partly in section and partly in elevation of the razor shown in Fig. 1, the blade and its holding means being shown rotated relatively to the guard as in sharpening the blade;

Fig. 3 is a view similar to Fig. 1 of a modified construction;

Fig. 4 is a view in elevation of a part used in the modification shown in Fig. 3;

Figs. 5 and 6 are views in elevation and plan, respectively, of the blade holder or support shown in Figs. 1 and 2;

Fig. 7 is a view in section of a modified construction of the sharpening means; and

Figs. 8 and 9 are views in section of parts shown in Figs. 1 and 2.

As shown in Figs. 1 and 2 of the drawing a razor constructed in accordance with this invention and arranged for use with double-edged blades comprises an inner tube 1 having a portion at one end of greater internal diameter to form a recess in which is mounted the collar 2 formed integral with the blade holder or support 4. Lugs 5 formed integral with the collar 2 and engaging in corresponding notches in the end of the tube 1 hold the blade support 4 fixed with respect to the tube 1. Mounted within the tube 1 is a rod 6 threaded at one end to receive a blade retainer 8 which is formed with spaced openings to receive the lugs 9 on the blade holder 4 which hold and position the blade 10 and the retainer 8.

Adjacent the threaded end, the rod 6 is formed with a hemi-spherical groove 11 in which is fitted a lock washer 12 of circular cross section which engages in the recess formed in tube 1.

Surrounding the inner tube 1 is an outer tube or barrel 14 having a blade guard 16 attached at

one end thereof. The center portion of the guard 16 is shaped to form a rectangular trough having parallel side walls 17 extending longitudinally of the blade guard at opposite sides thereof. Fixed within the barrel 14 is an annular collar 5 or bushing 18 forming a seat for a spool or sleeve 20 which surrounds the tube 1 and is flanged at both ends. Mounted on the sleeve 20 is a spring 22 which is confined between the inner flange of the sleeve 20 and the bottom of a blade sharpening or treating means 24 positioned in the trough formed in the blade guard 16. The spring 22 normally holds the blade treating means 24 against the outer flange of the sleeve 20 thereby limiting its movement to avoid displacement of 10 the blade holder 4 from its seat although maintaining the desired tension on the blade treating means 24. Further, it will be noted, the blade treating means 24 intersects the plane of the cutting edges of the blade 10 held by the blade 15 support 4 and the blade retainer 8.

At their opposite ends the tube 1 and rod 6 project beyond the end of the barrel 14 and in the end of the barrel 14 is fitted a shouldered bushing 26 which serves as a seat for one end of a 25 spring 28 confined between the bushing 26 and a collar 30 fitted in a groove in the outer face of the tube 1. Bushing 26, integral with barrel 14, is pressed against the collar 30 fitted into a recess 30 in tube 1 and thereby maintains the relative 35 position of guard 16 and blade holder 4. The end portion of the tube 1 is slotted, as at 29, to receive inwardly projecting lugs 31 formed on a sleeve 32 which is over sufficient length to overlap the end of the bushing 26 and is formed 35 with inwardly projecting lugs 33 engaging in slots 34 in the bushing 26.

A spring 36 confined between the sleeve 32 and a collar 38 tends to force the sleeve 32 outwardly but a knob or ball 40 pressed on the projecting end of the rod 6 limits the outward movement of the sleeve 32 to a position in which the lugs on the sleeve 32 are in engagement in the slots in the tube 1 and the bushing 26. With the sleeve 32 in this position the barrel 14 is held 45 against rotation relative to the tube 1. Inwardly of the lugs 33 the sleeve 32 has a portion with an internal diameter greater than that of the shouldered portion of the bushing 26 and of 50 sufficient length to receive the shouldered portion of the bushing.

The end of the barrel 14 adjacent the bushing 26 is of reduced external diameter so that the sleeve may be moved axially against the action 55 of spring 36 to disengage the lugs 33 from the

slots 34 thus disengaging the sleeve 32 from the barrel 14 while retaining the sleeve 32 connected to the tube 1. With the sleeve 32 in this position the barrel 14 can be rotated relatively to the tube 1, thus rotating the blade sharpening or treating means 24 with respect to the blade 10 and sharpening the blade. As the blade 10 contacts with the sharpening or treating means 24 the sharpening means 24 is moved along the tube 1 against the action of spring 22 which thereafter causes the sharpening means 24 to bear against the blade 10 with suitable pressure.

As the slots 34 in the bushing 26 and the lugs 33 on the sleeve 32 are diametrically arranged there are but two positions in which the sleeve 32 and bushing 26 may engage and in both of these positions the blade 10 and guard 17 are properly positioned for use.

The blade holder 4 is shaped to present a curved surface to the blade 10 so that the blade 10 is bent in the usual way when secured between the holder 4 and retainer 3. If desired narrow reinforcing ribs 42 may be formed integral with the blade holder 4, the ribs being of such dimensions that they perform no function in the positioning of the blade 10. Where the ribs 42 are used, the blade retainer 3 will be grooved to receive the ribs.

While the blade sharpening or treating means 30 may comprise a single block or piece of suitable material shaped to fit the trough in the blade guard 16 and formed with an opening to fit the sleeve 20 as shown in Figs. 1 and 2, the blade treating means may be formed of a plurality of pieces 44 and 46, as shown in Fig. 7. These pieces may be of the same or different materials, suitable for honing or stropping the blade as described, and are cemented or otherwise secured in a pan 48 which is formed with an opening to receive the sleeve 20.

To operate the structure shown in Figs. 1 and 2 to sharpen the blade 10 the sleeve 32 is moved axially on the tube 1 and barrel 14 toward the blade end until further movement of the sleeve 32 is prevented by the engagement of the lugs 31 with the ends of the slots in the tube 1. The sleeve 32 is now disengaged from the barrel 14 and the blade treating means 24 can be rotated to sharpen the blade 10. After the blade 10 is sharpened the sleeve 32 and barrel 14 are rotated relatively until the lugs 33 on sleeve 32 again engage in the slots 34 in bushing 26, whereupon the sleeve 32 is released and the spring 36 returns the parts to their normal positions.

In the modification shown in Fig. 3, the inner tube 50 has a portion of reduced diameter at one end forming a shoulder against which the blade support 52 is seated. Within the tube 50 is a rod 54 having a threaded end portion 55 of increased diameter which engages the end of the tube 50 and which is screwed into a correspondingly threaded opening in a blade retainer 56. The blade 10 is secured between the holder 52 and retainer 56 and the holder 52 engages the tube 50, blade 10 and blade retainer 56 as in the other construction.

Surrounding the tube 50 is an outer tube or barrel 58 to which is secured the blade guard 60. The barrel 58 is formed with an inwardly extending shoulder 62 which engages with a shoulder 64 on the tube 50 to limit movement of the barrel 58 and guard 60 in the direction of the blade 10 under the pressure of a spring 66 which surrounds the tube 50 and is confined between the shoulder 62 and a sleeve 68 threaded on the end

of the tube 50. The rod 54 projects beyond the end of the tube 50 and is threaded to receive a nut 70 which serves to hold the rod in the tube 50.

Adjacent the blade end there is a sleeve 72 which fits between the tube 50 and barrel 58 and carries a blade treating means 74, shown as of spring metal although it may be formed as shown in Fig. 1 or Fig. 7. The inner end of the sleeve 72 bears against the shoulder 64 and the sleeve 72 is of such length that the blade treating means 10 74 intersects the plane of the blade edges. The sleeve 72 is provided with a slot 76 through which extends a pin 78 which is fixed in the barrel 58 and engages in a straight slot 80 in the tube 50. The engagement of the pin 78 in the slot 80 of tube 50 permits relative axial movement of the barrel 58 and tube 50 which prevents relative rotation thereof. The slot 76 in sleeve 72 has its upper portion, as seen in Fig. 4, straight while the remainder of the slot is of spiral shape. The straight portion of the slot 76 permits of the withdrawal of the guard 60 from the region of the blade 10 and blade treating means 74 before the engagement of the pin 78 in the spiral portion of the slot 76 causes the sleeve 72 to be rotated, bringing the blade treating means 74 into engagement with the blade 10. Returning the barrel 58 to the position in which it is normally held by the spring 66 returns the blade treating means 74 to the position shown in Fig. 3 and puts the various parts in position for use. To operate this modification the barrel 58 is reciprocated axially.

What is claimed is:

1. In a safety razor for double edged blades, a 35 double-edged blade, a blade carrier, a blade guard and blade treating means mounted on said guard, and means supporting said blade guard for rotation relatively to the blade carrier to apply said blade treating means to the blade edges. 40

2. In a safety razor, a blade, a blade carrier, a blade guard, a blade treating means carried by said guard, means supporting said guard and carrier for relative rotation about an axis normal to said blade treating means and means lock- 45 ing said carrier and guard against relative rotation, said locking means being releasable to permit application of said blade treating means to said blade by relative rotation of said carrier and guard. 50

3. In a safety razor, a blade, a blade guard, blade treating means, means supporting said blade and blade treating means for relative rotation about an axis normal to said blade treating means and a connection between said blade treat- 55 ing means and guard operative to rotate said blade treating means in contact with said blade upon movement of said guard from and to guard- ing position.

4. In a safety razor, a blade, a blade guard, 60 blade treating means between said blade and guard, means supporting said blade and blade treating means for relative rotation about an axis normal to said blade treating means and a connection between said blade treating means and guard operative to rotate said blade treating means in contact with said blade upon move- 65 ment of said guard.

5. In a safety razor, a blade carrier, a blade 70 mounted thereon, a blade guard, blade treating means carried by said guard, means supporting said carrier and guard for relative rotation about an axis normal to said blade treating means to apply said blade treating means to the blade and 75

means yieldingly holding said blade treating means in contact with the blade.

6. In a safety razor for double edge blades, a blade carrier, a blade mounted thereon, a blade guard having a channel therein, means supporting said carrier and guard for relative movement and blade treating means carried in said channel and engaging both edges of said blade simultaneously upon relative movement of said carrier and guard.

7. In a safety razor, a blade, a blade carrier, a support for said blade carrier, a blade guard, blade treating means mounted to move with said blade guard, a carrier for said guard rotatably mounted on said blade carrier support and a sleeve on said blade carrier support interlocking with said blade carrier support and guard carrier to prevent relative rotation of said blade carrier support and guard carrier, said means being shiftable to free said blade carrier support and guard carrier for relative rotation whereby said blade treating means may be applied to said blade.

8. In a safety razor, a blade, a blade carrier, a support for said blade carrier, a blade guard having a centrally disposed longitudinally extending recess, a blade treating means mounted in said recess, a carrier for said guard rotatably mounted on said blade carrier support and means interlocking with said blade carrier support and guard carrier to prevent relative rotation thereof, said means being movable to permit relative rotation of said blade carrier support and guard carrier and application of said blade treating means to said blade.

9. In a safety razor, a blade, a blade carrier, a blade guard having a longitudinally extending recess therein, means supporting said carrier and guard for relative rotation and blade treating means mounted in said recess and rotatable with said guard to engage said blade.

10. In a safety razor, a blade, a blade carrier, a support for said blade carrier, a blade guard, a carrier for said guard surrounding said blade carrier support and a sleeve on said blade carrier support interlocking with said blade carrier support and guard carrier to hold said guard positioned with respect to said blade.

11. In a safety razor, a blade, a blade carrier holding said blade bent, a blade guard having a centrally disposed longitudinally extending recess, blade treating means carried by said guard and having the blade engaging surface thereof lying between the blade and the common plane of the blade edges and means supporting said blade carrier and guard for relative rotation to apply said blade treating means to the blade and remove it therefrom.

12. In a safety razor, a blade, a blade carrier

holding said blade bent, a blade guard having a centrally disposed longitudinally extending recess and blade treating means carried by said guard and intersecting the common plane of the blade edges, said carrier and guard being relatively rotatable to engage said blade treating means with said blade.

13. In a safety razor, a blade, a blade carrier holding said blade bent, a blade guard having a centrally disposed longitudinally extending recess and blade treating means carried by said guard and intersecting the common plane of the blade edges, said carrier and guard being relatively rotatable to engage said blade treating means with said blade and yielding means determining the engaging pressure of said blade and blade treating means.

14. In a safety razor, a blade, a support for said blade having a stem, a blade guard mounted for movement axially of said stem from and to guarding position, blade treating means, means supporting said blade and blade treating means for relative rotation and a connection between said blade treating means and guard operative to rotate said blade treating means in contact with said blade upon axial movements of said guard.

15. In a safety razor, a blade, a support for said blade having a stem, a blade guard mounted for movement axially of said stem, blade treating means between said blade and guard, means supporting said blade and blade treating means for relative rotation and a connection between said blade treating means and guard operative to rotate said blade treating means in contact with said blade upon movement of said guard.

16. In a safety razor, a blade, a blade guard, blade treating means, means supporting said blade and blade treating means for relative rotation about an axis normal to said blade treating means and a connection between said blade guard and blade treating means operative to effect relative rotation of said blade and blade treating means to engage said blade and blade treating means upon movement of said guard.

17. In a safety razor, a blade, a carrier for said blade, a guard for said blade, blade treating means carried by said guard and having the blade engaging surface thereof lying between the body of the blade and a plane extending through the edge of the blade parallel to the blade engaging surface, means supporting said blade carrier and guard for relative rotation to apply said blade treating means to the blade and means yieldingly holding said blade and blade treating means in contact upon relative rotation of said blade carrier and guard.
